AUTOMOBILE WINDOW REGULATOR

Thomas Raymond Bertsch, Farmington, Mich., assignor to Chrysler Corporation, Highland Park, Mich., a corporation of Delaware

Filed May 23, 1960, Ser. No. 60,678

Term of patent 7 years

(Cl. D10—8)

Fig. 1 is a front view of an automobile window regulator embodying my new design;

Fig. 2 is a top plan view thereof;

Figs. 3, 4 and 5 are sectional views taken on the lines 3—3, 4—4 and 5—5, respectively, of Fig. 1; and

Fig. 6 is a fragmentary sectional view on an enlarged scale of a portion of Fig. 3.

I claim:

The ornamental design for an automobile window regulator, substantially as shown.
